UNITED STATES PATENT OFFICE.

PAUL A. BERGMAN, OF PORTLAND, OREGON.

DESIGN FOR A PHONOGRAPH-CABINET.

57,882.

Specification for Design. Patented May 17, 1921.

Application filed February 8, 1921. Serial No. 443,475. Term of patent 7 years.

To all whom it may concern:

Be it known that I, PAUL A. BERGMAN, a citizen of the United States, residing at Portland, in the county of Multnomah and State of Oregon, have invented a new, original, and ornamental Design for Phonograph-Cabinets, of which the following is a specification, reference being had to the accompanying drawing, forming part thereof.

The figure is a perspective view of a phonograph cabinet showing my new design.

I claim:

The ornamental design for the phonograph cabinet as shown.

PAUL A. BERGMAN.
